UNITED STATES PATENT OFFICE

NICHOLAS JACOVATOS, OF NEW YORK, N. Y.

EXTENSIBLE TABLE.

1,107,954.

Specification of Letters Patent. Patented Aug. 18, 1914.

Application filed November 21, 1913. Serial No. 802,213.

To all whom it may concern:

Be it known that I, NICHOLAS JACOVATOS, a citizen of the Kingdom of Greece, and a resident of New York, in the county and State of New York, have invented certain new and useful Improvements in Extensible Tables, of which the following is a specification.

This invention has reference to improvements in extensible tables and pertains particularly to round tables which are usually supported by a central pillar.

Underneath the flat circular top of the table there are provided a multiple of attachments preferably four, which are normally hidden from view. These attachments may be drawn out either singly or in groups, or all of them in radial arrangement, or partly grouped together. By means of the attachments the extensible table may be transformed to answer various purposes, for instance, it may be converted into a card table when the attachments are radially arranged, each player having then one attachment to the right whereupon to place refreshments, chips or score sheets. For sewing or embroidering purposes several of the attachments may be arranged side by side with one attachment unused or opposite the group.

The extensible table may also be utilized to advantage in confectionery stores for placing glasses thereon filled with soda water and the like, while the central portion of the top may be used for exhibiting special brands of candy.

The tables further may be used in places where, under normal conditions, space should be economized.

The top of the table may consist of any of the usual materials employed for table tops such as wood, stone or metal. Wood, however, is the preferred material because wooden tables are light and the attachments with their accessories are easily and cheaply formed.

In order to render the invention entirely clear, reference is had to the accompanying drawings in which:

Figure 1 represents in top plan view an extensible table with four drawn out attachments arranged in radial style and showing a group arrangement of attachments partly in dotted lines. Fig. 2 is a bottom plan view with the attachments under the top showing in dotted lines the at-

tachments as drawn out. Fig. 3 represents the table in cross-section on line 3-3 of Fig. 2, on an enlarged scale. Fig. 4 shows detail views of one attachment. Fig. 5 illustrates in similar views another attachment.

Similar characters of reference denote like parts in all the figures.

In the drawings *a* represents the flat circular top. Underneath the top two rectangular oblong wooden blocks *b*, *c* are secured to its bottom in parallel lines. A long groove *d* is cut into the bottom portion of the top parallel to the two blocks *b*, *c* and at equal distance therefrom. The groove *d* extends somewhat beyond the center of the top and with its opposite portion to near the circumference. Two similar grooves *e*, *f* of approximately the same length run parallel to the groove *d* and the blocks *b*, *c*. These grooves are provided in the half of the top opposite to the groove *d* and extend somewhat beyond the center and with their opposite portions also to near the circumference of the top. The grooves *e*, *f* are also located within the blocks *b*, *c* and in close proximity thereto. There are further two shorter corresponding grooves *g*, *h* parallel to the other grooves and the two blocks, but located outside of the latter. Each of the grooves *g*, *h* extends somewhat beyond the center line of the top, as shown to the right in Fig. 3, and with the opposite portion at a larger distance therefrom, but not so close to the circumference of the top as the groove *d*.

In the table illustrated four attachments are provided of which the attachment *i*, shown in detail in Fig. 4, consists of a plate *i*¹ having a rounded outer portion *i*² and rectangular inner edge portions *i*³. From the inner plate portion a tongue *i*⁴ extends inwardly from its center. This tongue has formed thereon two small guide pins *j*, *k* which are purposed to travel in the groove *d* when this attachment is moved out or in. The attachment further has an incision *l*, preferably metal lined, which acts as a grip for a finger when the attachment is moved.

The attachment *m* which is located opposite the attachment *i* is of similar construction, as shown in Fig. 5 in detail. This attachment, however, has two narrow tongues *m*¹, *m*² parallel to each other. Each tongue *m*¹ has two guide pins *n*, *o* which are purposed to travel in the grooves *e*, *f* when the attach-

ment is operated. The space left between the narrow tongues m^1, m^2 , is so selected that the tongue i^4 finds room therein when the attachments are pushed together under the 5 top of the table. The width of the tongues m^1, m^2 is such that they fill the space between the tongue i^4 and the blocks b, c . In this manner the blocks act as guides for the tongues m^1, m^2 . The two other attachments

10 p, q are of like construction and represent essential oblong plates without any tongues. Each of these attachments has a metal lined incision r acting as a grip and each has one guiding pin near one corner which is rounded off, as shown in Fig. 2. The pin of the attachment p is adapted to travel in the groove h , and the pin of the attachment q in the groove g .

Assuming now that the four attachments 20 have been placed onto the reversed top so that none extends beyond said top then a circular plate s of smaller diameter than the top of the table is attached to the stationary wooden blocks b, c preferably by means of 25 screws t , as shown in Fig. 3. A pillar u is attached to the circular plate s in a convenient manner, thus completing the table. The plate s is secured to the wooden blocks b, c and the top a in such manner that the attachments may easily slide between the top 30 and said plate s .

When the table shall be converted, for instance, into a card table then the attachments i, m are drawn out as far as desired or 35 until the guide pins near the body portion reach the end of the grooves in which they travel. These two attachments are then opposite each other, as shown in Fig. 1. Now the attachment p is drawn out parallel to 40 the two attachments first drawn out, then the attachment p is turned around in an arc until its inner edge near the pin rests fully against the wooden block c . This movement is rendered possible by the rounded off portion 45 near the pin of the attachment which then is at a right angle to the two attachments first drawn out. In a similar manner the attachment q is drawn out and turned until its inner edge near the pin rests 50 against the block b . The four attachments thus are radially arranged and four players may sit one each between two attachments. The same arrangement may be made in confectionery stores and wherever space is to be 55 economized. Other arrangements of the attachments may be made, as shown, for instance, in Fig. 1, wherein the attachments

p, q are simply drawn out to rest against the attachment i , as shown in dotted lines. Only one of the attachments p, q may also be 60 drawn out and the outer surface arranged to be practically in line with the attachment i , as required, for instance, for sewing purposes and the like. The other attachments may then be drawn out or concealed as required for each specific purpose. 65

I claim as my invention:

1. An extensible table comprising a top having a multiple of parallel grooves in its bottom portion, two wooden blocks secured thereto in parallel lines to said grooves, a bottom plate secured to said wooden blocks, and a multiple of separate attachments between said plates having tongues with guide pins thereon and sliding in the grooves, said 75 attachments being adapted to be arranged at right angles to each other.

2. An extensible table comprising a circular top having a multiple of parallel grooves in its bottom portion, two wooden blocks secured thereto in parallel lines to the grooves, a somewhat smaller circular bottom plate secured to the wooden blocks, two oppositely arranged attachments having tongues with guide pins sliding in the inner 80 grooves, and two oppositely arranged attachments at right angles to the first with guide pins and one rounded corner each sliding in the outer grooves and adapted to be drawn out side by side with the first attachments or at right angles thereto. 85

3. An extensible table comprising a circular top having five parallel grooves in its bottom portion, two blocks secured to the center bottom portion of the top in parallel 95 lines to said grooves, an attachment with central tongue and guide pins sliding in the central one of said grooves, an attachment with two tongues and guide pins sliding in the two middle grooves along the blocks and the central tongue of the first attachment, and two attachments with one pin each sliding 100 each in an outer groove and having a rounded corner near the pin, so arranged that the four drawn out attachments may radially extend from the top, and a bottom plate smaller than the top secured to the blocks. 105

Signed at New York, N. Y., this 20th day of November, 1913.

NICHOLAS JACOVATOS.
